DESIGN FOR A DIFFUSER FOR A FLUORESCENT TUBE FIXTURE

Albert J. D. Ohm, Buffalo, N. Y., assignor to
Markel Electric Products, Inc., Buffalo, N. Y., a
corporation of New York

Application March 11, 1941, Serial No. 99,493

Term of patent 14 years

To all whom it may concern:

Be it known that I, Albert J. D. Ohm, a citizen of the United States, residing at Buffalo, in the county of Erie and State of New York, have invented a new, original, and ornamental Design for Diffusers for Fluorescent Tube Fixtures, of which the following is a specification, reference being had to the accompanying drawing, forming a part thereof.

In said drawing:

Figure 1 is a side elevational view of a diffuser

for fluorescent tube fixtures embodying my new design.

Figure 2 is a bottom plan view thereof.

Figure 3 is a top plan view.

Figure 4 is an end elevational view.

Figure 5 is an enlarged fragmentary section taken along line 5—5 of Figure 3.

I claim:

The ornamental design for a diffuser for a fluorescent tube fixture, substantially as shown.

ALBERT J. D. OHM.
